UNITED STATES PATENT OFFICE.

FLORA V. REAM, OF SOMERSET, OHIO.

DESIGN FOR A CURTAIN.

SPECIFICATION forming part of Design No. 28,620, dated May 10, 1898.

Application filed June 28, 1897. Serial No. 642,756. Term of patent 7 years.

To all whom it may concern:

Be it known that I, FLORA V. REAM, a citizen of the United States, residing at Somerset, in the county of Perry and State of Ohio, have invented and produced a new and original Design for a Curtain, of which the following is a specification, reference being had to the accompanying drawing.

This invention relates to a design for a curtain, substantially as hereinafter more fully described and claimed.

The accompanying drawing shows a curtain, as a new article of manufacture, made in accordance with my design.

15 Referring to the drawing, representing a completed curtain, the numeral 1 designates the outer edge of the curtain, which is continuous from side to side at the top. The inner edges consist of a series of straight 20 lines 2, connected by curved or scalloped lines 2', which form a series of spaces 3, gradually increasing in width from above downward. The curtain consists of a series of folds 4, the

lower edge of which extends inwardly and upwardly and then outwardly and upwardly, 25 the outer edge of each fold terminating at a point inside of the next longer fold.

The curtain consists of a series of folds terminating at the top with the abutting edge 5 of the upper fold and the edge of the material, as at 6. The succession of curved and straight lines form notches or scallops and complete a design which, from an esthetic point of view, makes a very attractive and beautiful curtain. 35

Having shown and described my invention, what I claim as new is—

The design for a curtain herein shown and described.

In testimony whereof I have signed this 40 specification in the presence of two subscribing witnesses.

FLORA V. REAM.
